TREASURE CHEST

Joseph A. Goodhue, Leominster, Mass.

Application November 27, 1953, Serial No. 27,816

Term of patent 14 years

(Cl. D58—11)

To all whom it may concern:

Be it known that I, Joseph A. Goodhue, a citizen of the United States, residing at Leominster, Massachusetts, have invented a new, original, and ornamental Design for a Treasure Chest, of which the following is a speculation, reference being had to the accompanying drawing, forming part thereof.

Fig. 1 is a top plan view of a treasure chest showing my new design;

Fig. 2 is a front elevational view thereof;

Fig. 3 is a rear elevational view thereof; and

Fig. 4 is an end elevational view thereof.

I claim:

The ornamental design for a treasure chest, as shown.
